WEB SUPPLY MECHANISM FOR PRINTING MACHINES

Albert J. Horton, White Plains, N. Y., assignor to R. Hoe & Co., Inc., New York, N. Y., a corporation of New York

Application December 7, 1935, Serial No. 53,315

28 Claims. (Cl. 242—58)

This invention relates to web supply mechanism for a printing or other machine operating upon a web drawn from a roll, and more particularly to improvements in web deflecting and severing means for use in machines having equipment for joining the web of a replacement roll to the web of an expiring web roll without stopping the machine. This invention especially contemplates the provision of means for actuating the 10 web severing knife, of a high speed web joining mechanism having a latching mechanism with a solenoid release for the web deflecting mechanism, which is operably connected to the knife release to actuate the same and thereby permit 15 the knife to sever the web.

One object of this invention is to provide an improved web deflecting and severing mechanism.

Another object is to provide in such a mechanism, provision to latch the brush carrying arm 20 of the deflecting mechanism to the knife carrying arm, and, after releasing the same, to cause further operation of the latch to release the knife to sever the web.

Still another object is to provide in a web deflecting and severing mechanism, a solenoid actuated latch for holding the brush carrying arm, and automatically operable mechanism actuated by the said solenoid for releasing the web severing knife to permit its operation.

A further object is to provide an improved form 30 of device for actuating and controlling a web deflecting and severing mechanism.

It is also an object of this invention to provide a web supply mechanism of generally improved 35 construction, whereby the device will be simple, durable and inexpensive in construction, as well as convenient, practical, serviceable and efficient in its use.

With the foregoing and other objects in view, 40 which will appear as the description proceeds, the invention resides in the combination and arrangement of parts, and in the details of construction hereinafter described and claimed, it being understood that various changes in the precise embodiment of the invention herein disclosed may be made within the scope of what is claimed without departing from the spirit of the invention.

The preferred embodiment of the invention is 45 illustrated in the accompanying drawings, wherein:

Figure 1 is a partial view, in elevation, of a web supply mechanism, embodying the features of this invention;

Figure 2 is an enlarged end view of the web de-

flecting and severing mechanism shown in Figure 1;

Figure 3 is a partial face view of the mechanism shown in Figure 2, looking in the direction indicated by arrow 3, in Figure 2;

Figure 4 is a section on line 4—4 of Figure 3, looking in the direction indicated by the arrows, showing the position of the parts after the release of the brush carrying arm from the knife carrying arm, and by dotted lines showing disposition of certain of the parts to permit the subsequent operation of actuating the web severing knife;

Figure 5 is a section similar to Figure 4, but showing the parts in knife release position;

Figure 6 and 7 are top plan views of the web severing mechanism looking in the direction as indicated by the arrow 6 in Figure 5, Figure 6 showing the knife protracted, and Figure 7 showing the knife in retracted position;

Figure 8 is a section on line 8—8 of Figure 6;

Figure 9 is a section on line 9—9 of Figure 6; and

Figure 10 is a section on line 10—10 of Figure 7.

The web supply mechanism selected to illustrate the features of this invention and shown in Figure 1, includes a rotatable web roll supporting reel 11 having arms 12 extending therefrom upon which web rolls 13, 14 and 15 may be rotatably mounted in accordance with the general practice. In this instance web roll 13 is the expiring roll from which the web 16 thereof, is directed over guide rollers 17 into a machine adapted to operate thereon, such as a printing machine. Roll 14 is the replacement roll, which is shown after the reel 11 has been rotated to position it in proper relation to the web 16 to have its web joined thereto. Roll 15 is another web roll in position to be moved into the position now occupied by roll 14, when occasion demands the same. In the web supply mechanism illustrated, provision is made for rotating the replacement roll 14 before and during the joining of its web with the web 16 of the expiring roll 13. The roll rotating means is herein indicated as comprising a driven belt 18 in driving engagement with the roll 14.

Electrical control means is also provided to insure proper timing action of the various parts and are herein illustrated diagrammatically in Figure 1. This control means includes a cam 19 mounted to rotate with the replacement roll 14 and adapted to actuate a control switch 21 to energize a solenoid 22, which is arranged and

adapted to operate as hereinafter described, in association with the web deflecting and severing mechanism of this invention. A manually operated control switch 23 is also provided, in this 5 instance, in association with a manually actuated, mechanism operating lever 24, which is swingably mounted for movement from the dotted position shown in Figure 1 into the full line position, where it is stopped by a lug 30 here- 10 in shown formed on a supporting bracket 20.

The web deflecting and severing mechanism herein shown is supported from a machine frame 25 by and between brackets 26, which extend downwardly from the frame 25, one at each end 15 of the reel 11 and which also support the guide rollers 17. This mechanism, for the purpose of this description, may be considered as being a combination of two devices operable in cooperation to join the web 16 with the web of the replacement roll 14. Both of these devices, one of which carries a web engaging and deflecting member, herein in the form of a brush 27, and the other of which carries a web severing knife 28, are pivotally mounted to each bracket upon 20 a common pivoting shaft 29, so they may be manually swung backward and upward out of the way, when they are not in use and also downwardly and forwardly into operative position as shown in Figure 1, by means of a handle 40.

30 The web deflecting member or brush 27 is mounted upon a supporting bar 31, which extends between arms 32 mounted upon the shaft 29. The web severing means or knife blade 28 is slidably mounted between a pair of bars 33 and 34, which are secured together by screws 35 and then extend between and are secured to arms 36 by bolts 37. The arms 36 are mounted upon the shaft 29 and are limited in the forward pivotal movement therewith by stop pins 38 35 mounted, one on each arm, and disposed to engage a lug 39 depending from each of the brackets 26. Sufficient movement of arms 36 is permitted however to allow members 27, and an edge of each bar 33 and 34, to engage and firmly 40 press against the web 16 under constant pressure of springs 41, one of which is secured to each arm 36 on a stud 42, and to the adjacent bracket 26 at 43.

50 The arms 32, with their supported web deflecting brush 27, are normally locked to the web severing mechanism by a releasable connection between the adjacent arms 32 and 36. This connection comprises a releasable spring retained catch member 44 secured to one end 55 of a shaft 45 which is pivotally mounted at its other end to the arm 36. The catch member 44 is adapted to engage a pin 46 on the arm 32 by a hook 47, formed on the catch member. One end of a lever 48, which extends oppositely to 60 the portion 47 of member 44, is secured to the shaft 45, adjacent the end thereof journaled in the arm 36, and is connected at its other end to the movable core 49 of the solenoid 22 by a link 51. The energizing of the solenoid 22 will 65 pull the core 49 to rock the catch 44 and release the pin 46 from the hook 47 permitting pivotal movement of the arms 32 relatively to the arms 36, toward the replacement roll 14, by a cable 52, which is secured to the arm 32 on a stud 53, 70 and to the lever 24 by a spring 50, which is secured to an end of an arm 54 movable with the lever 24 upon a shaft 55. The cable 52 is reeved over a suitably disposed pulley 56 rotatably mounted upon the machine frame 25. It will 75 be understood that when pressure is applied to

the manually actuated lever 24, the spring 50 causes the web deflecting brush 27, when the catch 44 is released to press the web 16 against a previously prepared adhesive covered area on the web of the replacement roll 14, to join the 5 webs together.

To insure that the above operation of the brush 27, upon the web 16, takes place when the adhesive covered area of the web of the replacement roll 14 is directly opposite the portion of the web 16 engaged by the brush 27, the electrical controls shown in Figure 1 are provided. The arrangement is such that when pressure is applied to the handle 24 tending through the spring 50 to press the brush 27 15 against the web 16, the control switch 23 may be closed by pressure upon a spring controlled thumb button 60, through an operating rod 70, which engages the actuating member of the switch 23, to permit energization of the solenoid 22 by the operation of the switch 21 when it, in turn, is closed by action of the cam 19. The cam 19 is arranged to time the operation of the switch 21 to insure proper position of the adhesive area on the web of the replacement roll in respect to the brush 27 so that this brush will press the webs together. This movement of the brush 27 may be limited by stops 57 secured to the arms 36 and disposed to be engaged by lugs 58 on the arms 32. 30

Directly after the above web joining operation takes place the web 16 running from the then expired roll, is severed by the knife 28, as it is protracted between the bars 33 and 34 in a shearing movement transversely across the 35 web, with which the bars 33 and 34 are in engagement. As herein shown, the shearing movement of the knife 28 is obtained by mounting it for sliding movement, under influence of a spring 59, between the bars 33 and 34 and under the 40 control of a plurality of angularly disposed guiding surfaces 61, formed in the bars 33 and 34, cooperating with studs 62, secured in and extending from both sides of the knife 28. The spring 59 is secured to the knife 28 at 63 and 45 to the member 34 by a bolt 64, and is tensioned to constantly urge the knife 28 into protracted position.

The knife 28 is normally retained against protraction by the spring 59, by means of a catch finger 65, mounted upon the end of a rock shaft 66, which is rotatably mounted in a bracket 67 secured to the bar 33 by a bolt 68. The finger 65 is under continuous urge of a coiled spring 69 to cause it to lie within a notch 71 (Figure 55 6), formed in the knife 28, when the latter is in retracted position wholly between the bars 33 and 34 with its cutting edge covered thereby. A lever 72 mounted upon the shaft 66 is adapted to rock the finger 65 out of the notch 71 to 60 release the knife 28. The knife 28 may be withdrawn from its protracted position by any suitable means such as the herein shown lever 73 pivoted to the bracket 67 by a screw 74 and being secured at one end to one of the studs 65 62. A handle 75 is provided on the other end of lever 73 for use in the manipulation thereof for the above purpose.

Provision is made for rocking the lever 72 by actuation of the catch member 44 at the next 70 revolution of the replacement roll 14 after the webs are joined as above described. Herein, the means for rocking the lever 72 comprises an arm portion 76 on the member 44 extending oppositely to the hook portion 47 having a pin 77 75

mounted thereon in position to be engaged by a link 78 in a notch 79 formed therein. The link 78 is continuously urged toward the member 44 and pin 77 by a spring 81 secured at one end to a stud 82 on the arm 32 and at the other end to the link 78. A stop pin 83 on the arm 32 is positioned, to prevent cooperating engagement of the pin 77 in the notch 79, when the arm 32 is in connected relation with the arm 36 as shown in Figure 2, and to permit the engagement of the pin 77 in the notch 79, when the arm 32 is moved to the position shown in Figure 4.

After being actuated by the solenoid 22 to release the arm 32 from the arm 36, the catch member 44 is returned to its normal position by means of a coiled spring 84 acting upon the shaft 45 by having one of its ends secured to a collar 85 secured to the shaft, and its other end secured to the arm 36. This position of member 44 is shown in dotted lines in Figure 4. The spring 81 now pulls the link 78 toward the pin 77 whereby it is engaged in the notch 79 and by energization of the solenoid at the next revolution of the roll 14 due to action of the cam 19 on the switch 21, the core 49 pulls upon the link 51 to rock the member 44 into the position shown in Figure 5. This movement actuates the link 78 to rock the lever 72 and removes the finger 65 from the notch 71. As above explained, this action permits the knife 28 to be protracted by the spring 59 to sever the web 16.

The electrical circuit may be arranged as shown wherein a conductor 91 leads from a line wire L1 to the switch 23 from which a conductor 92 leads to the solenoid 22. From the solenoid 22 a conductor 93 continues the circuit to a contact ring 94 rotatable with the reel 11. From the ring 94 the circuit continues through a suitable automatically operable switch 95 herein shown as being of the mercury type, from which a conductor 96 leads to the switch 21 and thence to another contact ring 98 by way of conductor 97 from which a conductor 99 leads to the other line wire L2. A cam 19, a switch 21, and a switch 95 is provided on each arm of the reel 11 and in view of its construction, each of the switches 95 are in closed circuit condition only when the arm upon which it is mounted is in position to dispose a replacement web roll in web joining position.

Briefly the operation of the above described mechanism is as follows:

It will be assumed that the replacement roll 14 has been moved into the position shown in Figures 1 and 2 by rotation of the supporting reel 11 and that the replacement roll has been prepared by having adhesive applied to its web and is being rotated at the proper speed by the belt 18. The attendant presses downwardly upon the lever 24 which through the spring 50 causes a pull to be applied through the cable 52, upon the arm 32. However, actuation or movement of the arm is restrained by the catch 44. Cam 19 due to its rotation with the roll 14 actuates the switch 21 to complete the circuit to the solenoid 22, to energize the same when the adhesive covered area on the web of the replacement roll 14 is in proper position to have the web 16 pressed against the same by the brush 27 after the attendant has pressed the button 60 to close the switch 23. Energization of the solenoid 22 actuates the catch member 44 through the movable core 49 and the link 51 to release the arm 32 from the arm 36 and permit its movement toward the roll 14 to press the web 16 thereagainst. Continued rotation of

the roll 14 allows the switch 21 to open after the cam 19 has passed and deenergize the solenoid 22, permitting the catch member 44 to be positioned by the action of the spring 84 to engage the link 78 of the web severing mechanism and on the next rotation of the roll, the cam 19 again closes switch 21 and the solenoid 22 is again energized as previously explained to actuate the link 78 and rock the lever 72 to release the web severing knife 28.

From the foregoing description, it will be seen that a mechanism has been provided, whereby with a single solenoid and a simple electric circuit a web deflector and a web cutter may be caused to operate in proper timed relation to effect the joining of the web of a replacement web roll to the web of an expiring web roll and then sever the latter.

It will be understood that the invention may be embodied in other specific forms without departing from the spirit or essential attributes thereof, and it is therefore desired that the present embodiment be considered in all respects as illustrative and not restrictive, and it will be further understood that each and every novel feature and combination present in or possessed by the mechanism herein disclosed forms a part of the invention included in this application.

What I claim is:

1. In a web supply mechanism adapted to join a running web to the web of a replacement roll, an actuation restrained web deflecting device, an actuation restrained web severing device, and common means operable first to release and permit actuation of said web deflecting device to join the webs and again after the join is made to release said web severing device.
2. In a web supply mechanism adapted to join a running web to the web of a replacement roll, an actuation restrained web deflecting device, an actuation restrained web severing device, common means operable first to release and permit actuation of said web deflecting device to join the webs and again after the join is made to release said web severing device, and means to actuate said common means.
3. In a web supply mechanism, an actuation restrained web deflecting device, an actuation restrained web severing device, common means operable to successively release and permit actuation of said web deflecting device and said web severing device, and a single solenoid adapted to actuate said common means for both operations.
4. In a web supply mechanism, an actuation restrained web deflecting device, an actuation restrained web severing device, a swingable member operable to successively release and permit actuation of said web deflecting device and said web severing device, single means to actuate said member, and control means for said single means to alternate the operation of said devices.
5. In a web supply mechanism, an actuation restrained web deflecting device, an actuation restrained web severing device, and common means operable in timed relation with the rotation of a replacement roll to first release and permit actuation of said web deflecting device and after an interval dependent on the speed of the roll, to release said web severing device.
6. In a web supply mechanism for a printing machine, a web deflecting device, a web severing device, means to actuate said web deflecting device, common means operable in timed relation with the rotation of a replacement roll to first permit actuation of said web deflecting de-

- vice and after an interval dependent on the speed of the machine to permit actuation of said web severing device, and control means for said common means to alternate the operation of said devices.
7. In a web supply mechanism, means to rotatably support a replacement roll adjacent to a running web, a web deflector, a web severing device, releasable mechanism to actuate said web deflector to engage the running web, releasable mechanism to actuate said web severing device, and timing means rotating with the replacement roll to release said first mechanism during one revolution of the roll and to release said second mechanism during the next revolution of the roll.
8. In a web supply mechanism, means to rotatably support a replacement roll adjacent to a running web, a web deflector, a web severing device, releasable mechanism to actuate said web deflector to engage the running web, releasable mechanism to actuate said web severing device, common means operable to release both of said mechanisms, and control means for said common means to cause operation of the same to release said first mechanism during one revolution of the replacement roll and to release said second mechanism during the next revolution of the roll.
9. In a web supply mechanism, a swingable arm having a web deflecting member thereon, another swingable arm having a web severing device thereon, restrained means to actuate said severing device, a common supporting shaft for said arms, means to releasably connect said arms, and common means to release said arm connecting means and to release said severing device actuating means in sequence.
10. In a web supply mechanism, a web deflecting member, a web severing device, said member and said device being movable in the same direction, releasable means connecting said member to said device, restrained means to actuate said severing device, means to operate said releasable means to release said member from said device and to release said restrained severing device actuating means, and means to prevent operation of said releasing means to release said severing device actuating means, before it has operated to release said member from said device.
11. In a web supply mechanism, a web deflecting device, a web severing device, said devices being movable in the same direction, a rockable member pivoted to one of said devices and adapted to releasably engage the other to connect them together, restrained means to actuate said web severing device, means associated with said rockable member to release said restrained severing device actuating means, and means to rock said rockable member.
12. In a web supply mechanism, a web deflecting device, a web severing device, said devices being movable in the same direction, a rockable member pivoted to one of said devices and adapted to releasably engage the other to connect them together, restrained means to actuate said web severing device, means associated with said rockable member to release said restrained severing device actuating means, and an electrically energized solenoid adapted to act on said rockable member to actuate the same.
13. In a web supply mechanism, a web deflecting device, a web severing device, said devices being movable in the same direction, a latch pivoted to one of said devices and adapted to releasably engage the other to connect them together, restrained means to actuate said web severing device, means associated with said latch to release said restrained severing device actuating means, and together, restrained means to actuate said web severing device, means operable by said latch to release said restrained severing device actuating means, an electrically energized solenoid adapted to act on said latch to actuate the same, a circuit interrupter in circuit with said solenoid, and mechanical means to actuate said circuit interrupter to control the operation of said solenoid.
14. In a web supply mechanism, means to engage and deflect a running web toward a rotat- 10 ing replacement roll, means to sever the running web, means to connect said deflecting and said severing means, including a latch member on one of said means and a part on the other engageable by said latch, means to actuate said 15 web severing means, a rockable lever to restrain said actuating means, and means to release said latch during one revolution of the replacement roll and to rock said lever to release said actuating means during the next revolution of the roll. 20
15. In a web supply mechanism, means to engage and deflect a running web toward a rotating replacement roll, means to sever the running web, means to connect said means, including a latch member on one of said means and a part 25 on the other engageable by said latch, means to actuate said web severing means, a rockable lever to restrain said actuating means, an electrically operated solenoid adapted to rock said latch to release the same, connectable means between said 30 latch and said lever, and means to first energize said solenoid to cause rocking of said latch to release the same and then to energize said solenoid to cause said lever to rock to release the actuating means for said web severing means. 35
16. In a web supply mechanism, means to engage and deflect a running web toward a rotating replacement roll, means to sever the running web, a rockable catch on said web severing means adapted to engage a member on said web deflecting means to releasably connect said means, a restrained spring to actuate said web severing means, a rockable lever adapted to release the spring, connectable means between said catch and said lever, and a solenoid having a movable core, said core being adapted to release said catch when first acted upon by said solenoid and to actuate said connectable means to rock said lever and release said spring when again acted upon by said solenoid. 40
17. In a web supply mechanism, means to engage and deflect a running web toward a rotat- 45 ing replacement roll, means to sever the running web, a rockable catch on said web severing means adapted to engage a member on said web deflecting means to releasably connect said means, a restrained spring to actuate said web severing member, connectable means between said catch and said lever, a solenoid having a movable core, said core being adapted to release said catch when first acted upon by said solenoid, and to actuate said connectable means to rock said lever and release said spring when next acted upon by said solenoid, and means operable in 50 timed relation with the rotation of the replacement roll to energize said solenoid during successive rotations of said roll. 55
18. In a web feeding device adapted to change the web lead running to a machine, from an expiring roll to a replacement roll, a web deflector adapted to press the running web against the replacement roll, a web severing device, electro-responsive means to time the operation 60
- 75

of the web deflector and the severing device, and a timing device rotatable with the replacement roll and adapted to actuate the electro-responsive means to time the operation of the web deflector 5 during one rotation of said timing device and to time the operation of the severing device during its next rotation.

19. In web supply mechanism, a swingable arm having means thereon to engage and deflect a 10 running web toward a rotating replacement roll, means to releasably retain said arm, a manually operable member for moving said arm, and a resilient member to connect said arm and said member whereby, upon actuation of said manually 15 operable member, said arm will be placed under urge of said resilient member and when released for movement by said retaining means will engage and deflect the running web.

20. In a web supply mechanism, a web engaging and deflecting means including, a swingably mounted arm, releasable means to maintain said arm against movement, an electrically actuated member for releasing said means to permit movement of said arm, an electrical control for said 25 member, a device for moving said arm including, a manually operable member and a resilient connection between said last named member and said arm, and a separately manually operable part associated with said manually operable member 30 to actuate said electrical control.

21. In a web supply mechanism, a first means to engage and deflect a running web toward a replacement roll, an operating member, a releasable means normally restraining movement of the 35 said first means, and a second means resiliently connecting the first means and the operating member, whereby the operating member may be moved to bias the first means toward operating position, and when said first means is released, 40 it will operate to deflect the running web without additional movement of the operating member.

22. In a web supply mechanism, in combination, a restrained swingable device mounted to engage and deflect a running web toward a rotat- 45 ing replacement roll when released, a manually movable member, means to connect said member to said device including a spring, said member when moved in one direction being adapted to tension said spring to impose a pull upon said 50 device to swing it toward the replacement roll, and means to release said device.

23. In a web supply mechanism, in combination, a restrained swingable device mounted to engage and deflect a running web toward a rotat- 55 ing replacement roll when released, a manually movable member, means to connect said member to said device including a spring, said member when moved in one direction being adapted to tension said spring to impose a pull upon said 60 device to swing it toward the replacement roll, means to release said device, and means to limit the operating movement of said member.

24. In a web supply mechanism, in combination, a device mounted to engage and deflect a running web toward a rotating replacement roll, means to retain said device out of web deflecting position, means to release said retaining means, a movable member, means to connect said member to said device including a spring, said member when moved to an operative position being adapted to cause said spring to impose a pull upon said device toward the replacement roll, and means adapted to be operated to cause actuation of said releasing means after said member is moved to its operative position.

25. In a web supply mechanism having means to press a running web against a replacement web roll and to sever the said web, an actuating device, a deflecting member operable to press the web against the roll, a severing member operable to sever the web, and means actuated by the actuating device and in timed relation with the rotation of the replacement roll to first effect operation of the deflecting member and to subsequently effect operation of the severing member.

26. In a web supply mechanism, a web deflector adapted to press the web running from an expiring roll against the surface of a replacement web roll, a severing device adapted to sever the web of the expiring roll, means to bias the web deflector into web pressing position, means to bias the web severing device into web severing position, means to restrain the web deflector, means to restrain the web severing device, and electrically operated means actuated by rotation of the replacement roll for releasing said deflector restraining means and said device restraining 30 means successively.

27. In a web supply mechanism, means to rotatably support a replacement roll adjacent a running web, electrically actuated means to move the web and the roll relatively and into engagement with each other, an electrically actuated web severing device, and electric switch mechanism in circuit with said electrically actuated means and operated by rotation of the web roll to time the actuation of said moving means and then time the actuation of said web severing device to insure engagement of the web with the roll in advance of the operation of the web severing device.

28. In a web supply mechanism, means to rotatably support a replacement roll adjacent to a running web, a web deflector, a web severing device, a releasable mechanism to actuate said web deflector to cause it to engage the running web, a restrained mechanism to actuate said web severing device, means to release said mechanisms, and control means including timing means rotating with the replacement roll to effect the successive actuation of said releasable and restrained mechanisms.

ALBERT J. HORTON.
